OIL WELL PUMP

Geoffery Guy Basher, Bakersfield, Calif.

Application March 15, 1934, Serial No. 715,744

2 Claims. (Cl. 103—190)

My invention relates to oil well pumps and same relates more particularly to double-acting pumps, and an object of the invention is to provide means whereby a relatively constant column of oil will be maintained in the entire system and drawn upon during the regular functioning of the pump and the oil thus continuously flowed from the well.

An important feature of the invention attaches to the novelty residing in the pumping assembly, the form of which is such that it may be readily dropped to its working position and operatively correlated to the parts with which it is designed to co-act.

15 A still further object is to provide a pumping assembly wherein means are employed for preventing leakage between the parts employed, whereby to enable the plunger to operate with no appreciable loss of efficiency and with a resulting uniform lift upon the oil.

With the above and other objects in view, which will appear as the nature of the invention is better understood, the same consists in the improved construction and novel arrangements 25 of parts which will hereinafter be fully described and particularly pointed out in the accompanying claims.

In the drawings has been illustrated a single and preferred embodiment of the invention, it 30 being, however, understood that no limitations are necessarily made to the precise structural details therein exhibited, but that changes, alterations and modifications within the scope of the claims may be resorted to when desired.

35 In the said drawings,

Figure 1 is a vertical section through the upper part of the casing of a well showing the application of the invention thereto, the plunger being illustrated at the approximate position that it 40 occupies at the beginning of its up stroke;

Figure 1A is a view similar to Figure 1, illustrating the lower continuations of the parts;

Figures 2 and 2A are views similar to Figures 1 and 1A, with the plunger occupying a down stroke position;

Figure 3 is a detail section of the valve structure of the liner assembly;

Figures 4 and 5 are cross-sectional views taken, respectively, on the lines 4—4 and 5—5 of Figure 3;

Figure 6 is a section on the line 6—6 of Figure 1;

Figure 7 is a section on the line 7—7 of Figure 1A;

Figure 8 is a perspective view of the ring employed in the valve structure of the liner assembly;

Figure 9 is a view in side elevation of the spaced-apart inner liners, the connecting tube therebetween being shown partly broken away;

Figure 10 is a view in side elevation of the pump barrel, a part thereof being broken away for the purpose of clearness.

In practice, use is made of the customary well casing 15, tubing sections 16, pump barrel or cylinder 17, and sucker rod 18, the latter including a working valve 19. The lower end of the barrel or cylinder 17 is threadedly joined at 20 to a hollow, valved tube 21, and at the bottom of the latter is the downwardly tapered nose 22, adapted to seat within the correspondingly tapered seat 23 of the ordinary form of shoe 24. The upper end of the tube 21 has an exteriorly threaded reduced portion 25 to which is attached 10 the cage of a standing valve 26, the ball 27 of which is adapted to coat with the annular seat 28 formed upon the portion 25. It follows that because of the aforesaid construction of the tube 21, the said standing valve is contained within the lower end of the pump barrel or cylinder 17, where it may operate to control communication between said barrel or cylinder and the bore 21a of the tube 21. The lower end of the tube 21 is provided with an annular series of standing valves 29. These valves are thus disposed between the outer walls of the tube 21 and the inner walls of the lower tubing section 16, and the ports 30 in the cages of these valves are 20 adapted to discharge oil to the intervening space A between said tube 21 and said lower tubing section 16. The elbows 31 of said valves 29 open into the bore 21a of said tube, whereby communication may be established between said intervening space A and the said bore of the tube 21, as these valves function in practice.

Extending between adjacent tubing sections 16 and threadedly connected therewith at 32 and 32a is an outer sealing liner 33 in which are very 45 snugly fitted the companion inner sealing liners 34—34, the lower one of which is threadedly connected at 35 with the upper end of the pump barrel or cylinder 17, and it will be noted that just below said last named connection 35 and 50 50 formed in the said barrel or cylinder 17 are ports 36 through which oil may find passage thereto from the aforesaid space A. The upper end of the upper one of said inner sealing liners has threadedly connected therewith a standing 55

valve 37 whose cage structure is formed with the elongated large-area ports 38, the latter opening into the space B between the inner walls of the adjacent tubing section 16 and the exterior walls 5 of a hollow pump rod 39, the latter having threaded connection at 40 with the seat section 41 of the aforesaid working valve 19. Said hollow pump rod finds sliding passage through the cap of the cage structure of the valve 37, as at 10 37a, and the said rod thus constitutes a guide for the reciprocal valve ring 42 of said valve, whereby the ring may move to occupy either the closed position shown in Figure 2 or the open position shown in Figure 1. Now it will be observed that the lower one of the inner liners 34 15 is formed with an annular series of longitudinal ports 43 of arcuate form in plan and of large area, and that the other one of these inner liners is formed with similar ports 44, the upper ends of 20 which are adapted to open into the cage of the valve 37 when the valve ring 42 is open, as shown in Figure 1. Said ring 42 is formed with an annular tapered portion 45 (Figures 3 and 8) adapted to co-act with a correspondingly formed seat 25 46 in the upper end of the upper one of the said inner liners 34. The upper face of the lower one of the inner liners 34 and the lower face of the upper one of these liners are spaced apart from each other to provide an intervening large chamber C therebetween and said liners are connected by means of a hollow tubular guide 47 through which and through the coaxial bores 48 of the liners 34 the hollow pump rod 39 freely passes, in order that it may reciprocate as intended. 30 35 This rod proceeds into the pump barrel or cylinder 17, and same is fitted with an elongated cylindrical plunger 48 in which is formed a relatively large-area axial bore 49, by means of which communication is established between the cylinder 40 17, above the standing valve 26, and the bore 2ta of the tube 21.

I wish to call particular attention to the fact that nose 22 has a maximum diameter which is the same as that of the external diameter of the 45 pump cylinder 17, and that the standing valves 29 fall within the boundary line of a circle, the diameter of which is not greater than the said maximum diameter of the nose 22 or that of said pump cylinder, whereby it may freely pass 50 through the axial bore of the outer liner 34 when lowering the entire pumping assembly into or removing same from the well.

I wish further to stress the fact that the joint between the exterior face of upper end of the 55 pump cylinder 17 and the interior face of the outer liner 34 are so closely or snugly related to each other as to positively prevent any leakage therebetween and that, for like reason, the walls of the bores of the companion liners 34 fit very 60 closely the correlated external walls of the hollow pump rod 39.

Having thus fully described the essential structural features of the pump and the co-acting relationship of one part to the other, the operation of the pump will be briefly but sufficiently set forth as follows:

In Figures 1 and 1A the pump assembly has been fully lowered to a working position and the plunger 48 is illustrated as occupying the beginning of an upstroke movement. It follows that in the upstroke movement of said plunger, a strong suction will be induced in the barrel 17 and that this will exert a closing pull on the standing valves 29. The working valve 19 will 70 close as herein shown, in consequence of fluid

pressure exerted thereupon in the tubing 16, and the standing valve 26 will have assumed a position of open adjustment because of the suction induced in the barrel 17. The valve 42 will take an open position by reason of a lifting pressure 5 formed in the ports 43 and 44.

The flow course is now upwardly through the tube 21, through the cage of the valve 26 and into the pump barrel. Oil obviously admitted to the said barrel above the plunger and through ports 10 36 will be forced upwardly through the ports 43 and 44 and will pass the valve 42 and enter the space B in the tubing 16.

Because of the close fit of the structural parts of the liner assembly, air and oil leakage between 15 these parts and between the inner liners 34-34 will be effectively prevented so that the plunger 48 will constantly operate at maximum efficiency on both movements of the plunger.

On the downstroke of said plunger 48 (Figures 20 2 and 2A) the ball 21 will close against its seat 28 by fluid pressure formed above the same, and communication between the barrel 17 and tube 21 thus prevented, and oil which is thus trapped in the barrel below the plunger will be forced 25 through the latter and through the plunger rod 39 so as to open the valve 19 and enter the space B. The valve 19 will open, likewise the standing valves 29, the latter by virtue of the suction induced at the ports 36 and the former by the action of pressure formed above said valve 21. The valve 42 will firmly close against its seat 46 by the force of suction created beneath same. The course of the flow is now from the well, through the valves 29, then upwardly through space A into 30 the ports 36, and thence to the barrel 17, thereby replacing the oil discharged from the system on a previous upward movement of the plunger. It is because thereof that the entire system is constantly filled with oil and that on the two movements of the plunger as herein described oil will 35 be continuously discharged from the system.

It should be particularly borne in mind that when dropping the barrel 17 into the well to establish registration of the nose 22 with the 45 shoe 24, the crown wall 26a of the cage of valve 26 is axially related to the lower flat fluid-compressing end 48a of the valve 26, whereby to allow said end to be forced against said crown wall with the result that said nose 22 will be 50 firmly driven home or into operative co-action with the shoe 24.

The entire pumping system is of simple construction, the parts employed being exceedingly sturdy and compactly co-ordinated, and the 55 pumping assembly, as well as the tubing string herein employed, may be readily pulled from the well whenever desired.

By spacing the liners 34-34 from each other to provide the aforementioned large diameter 60 chamber C between the opposed or confronting ends thereof and between tube 47 and the inner walls of the outer liner 33, a relatively constant column of oil would be maintained in said chamber so that the flow of oil from the pump will be 65 continuous. During the downstroke of piston 48, at which time oil will be sucked into the pump barrel, a column of oil will form in the barrel directly beneath the ports 43. During the upstroke of said piston, the column of oil above the 70 piston will be forced against the column in said chamber C and the column in said chamber discharged into the space B through the standing valve 42. In this manner and assuming that a column of oil is maintained in space B and in 75

the flow space between tubing 16 and casing 15, the column in space B will remain relatively constant. It will, therefore, be appreciated that a constant column of oil will be maintained in the pump from the bottom of the well to said space B and that in consequence thereof, the flow of oil from the system will be continuous in response to respective reciprocal movements of piston 48.

10 What is claimed is:

1. In an organization of the class described, an elongated outer tubular liner formed at its respective ends for attachment to axially spaced apart ends of respective sections of vertically aligned tubing; a pair of axially spaced apart upper and lower inner liner frictionally fitting within the outer liner to provide a fluid tight joint between the inner walls of the outer liner and the external walls of the inner liners, said inner liners formed with aligned axial bores and each of said liners being of a length relative to the length of the outer liner to provide an oil chamber within the outer liner between confronting ends of the inner liners, a hollow tubular pump rod guide connecting the bores of said inner liners together; a pump rod movable through the axial bores of the inner liners and through the hollow tubular pump rod guide connecting the bores of said inner liners together; the pump rod guide and said axial bores serving to provide a long continuous bearing for the pump rod extending throughout the length of the outer liner, a pump barrel formed for attachment to the bottom of the lower inner liner; a piston at the lower end of the pump rod and reciprocable in the pump barrel; the inner liners

having ports, the inner ends of which open to said chamber and the other ends thereof to the aforementioned pump barrel and a section of the tubing, respectively, for upward passage of oil to the chamber from said pump barrel and discharge of the oil into said tube section from said chamber, a valve for closing the ports of the upper inner liner during reciprocal movement of the piston in one direction and valve means for admitting fluid to said pump barrel.

2. A chamber forming and liquid by-passing organization for use with a double acting oil well pump employing tubing, a valved pump barrel therein and a piston in the barrel through which liquid can pass, the same having a valved rod formed for passage of liquid from the pump barrel when the piston is moved in one direction, comprising a long vertically disposed outer liner formed at its ends for connection with respective sections of the tubing above the pump barrel; and a plurality of short vertical inner liners disposed one above the other and frictionally fitting the inner walls of the outer liner to provide a fluid-tight connection therewith and spaced apart from each other to provide a liquid chamber between same and within the outer liner, said inner liners each being ported to admit liquid to the chamber from the pump barrel and enable liquid in the chamber to pass therefrom and into the tubing above the respective liners, the uppermost inner liner having an upwardly opening valve movable to respectively cover and uncover the port therein; and means of which the inner liners form co-operable parts adapted to slidably receive the rod of the pump piston.

GEOFFERY GUY BASHER.
